UNITED STATES PATENT OFFICE

GEORGE J. SEISS, OF TOLEDO, OHIO

CAP FOR VAPOROUS LIQUID TANKS

Application filed December 1, 1930. Serial No. 499,293.

My invention has for its object to provide a cap or cover for the mouth of a tank or container in which a liquid may be stored. The invention has for its particular object to provide a readily removable, durable cap for a tank or container, for containing volatile liquids and having rigid engaging parts and a protected vent for maintaining atmospheric pressure, notwithstanding withdrawal of the liquid or its evaporation.

The invention may be contained in caps that vary in their details of construction and, to illustrate a practical application of the invention, I have selected a cap containing the invention as an example of the various forms of structures that embody the invention, and shall describe the cap selected, hereinafter. The cap selected for purposes of illustration is shown in the accompanying drawings.

Fig. 1 illustrates a perspective view of the cap in an inverted position. Fig. 2 illustrates a cross section of the cap and container opening when the cap is installed over the opening. Fig. 3 illustrates a cross section of the cap in an inverted position. Fig. 4 illustrates an enlarged cross sectional view of the top portion of the cap.

The invention provides a cap which is particularly adaptable to cover openings of containers for liquids, and from which the liquids are withdrawn. The cap is held about the opening of the container by a pair of legs. Portions of the legs engage the neck of the opening to hold the cap tightly over the opening. The legs are bent to have a channeled shape in cross section which greatly strengthens the legs against distortion or bending when the legs engage the neck of the opening. The construction of the cap prevents the entrance of air other than that which is required to prevent the existence of a vacuous condition in the tank due to withdrawal of the liquid. The cap likewise prevents the escape of air from the container which may contain a substantial amount of volatilized fluid, which may be in the container, thereby reducing the tendency of the liquid to evaporate. The cap also prevents the escape of the liquid through the

opening by the splashing action of the liquid within the container.

The cap 1, shown in the drawings, has a flange 2. The flange 2 has, substantially, the diameter of the exterior of the neck 3 of the opening 5 of the container 4 that is closed by the cap.

The cap 1 is held in position about the neck 3 of the container opening 5 by a U-shaped member 9. The U-shaped member 9 is located in the top portion 8 of the cap 1 and is secured thereto by rivets 10 which engage the web 16 of the U-shaped member 9 and the top portion 8 of the cap. The rivets 10 firmly hold the cap in a fixed relation with the U-shaped member and resists separation of the U-shaped member and the cap.

The U-shaped member 9 is formed to have legs 11 having horizontally extending portions 13 which are adapted to engage portions of the neck of the opening of the container. The legs 11 and horizontally extending portions 13 are bent to have a cylindrical channeled shape in cross section which strengthens the legs and horizontally extending portions against a bending movement when the cap is installed over the opening of the container and allows for ease of operation of the extending portions 13 over the inner edge portions 12, of the neck 3 of the opening, when the cap is being affixed over the opening.

The neck 3 of the opening 5 has inner edge portions 12 which form cam surfaces 14. The portions 13 are adapted to ride over the cam surfaces 14 to increasingly draw the cap tightly down on the opening to effect a substantially tight covering which will prevent the escape of the liquid which may be contained within the container.

In order to allow for the entrance of air in the container 4, as it is emptied, I provide a small opening 15 in the top portion 8 of the cap. An opening 17 is likewise formed in the web 16 of the U-shaped member 9. The opening 17 has a collar 18 which extends around it. The collar 18 is formed so that its edges are inclined towards each other to prevent the escape of liquid which may be contained in the container by splashing of the liquid. The collar also forms a chamber

20 which tends to prevent the rapid escape of air from within the tank which may contain volatilized portions of the liquid thereby cutting down the evaporation of the liquid by
5 reason of the substantial inactivity of the air located within the chamber 20.

A suitable washer 21 formed of cork, rubber, or some equally cushioning material, may be located about the edges of the top
10 portion 8 so as to cushioningly engage with the opening 3 and effectively seal it.

I claim:

1. In a cap for a container for vaporizable liquids, the container having a neck, the neck
15 having inturned cam shaped flanges, the cap having a centrally outwardly protruding dome shaped part, the dome shaped part having a central opening, a sheet metal member secured centrally to the cap and having a circular disc shaped central portion, the disc shaped central portion having an opening, the opening having a diameter substantially the same as the major diameter of the said dome shaped portion, the disc shaped portion
20 having a flange surrounding the said opening and projecting inwardly with respect to the container, legs extending radially from the periphery of the disc shaped portion and formed integral with the disc shaped portion
25 having a flange surrounding the said opening and protruding to engage the flanges of the neck.

2. In a cap for a container for evaporizable liquids, the container having a neck, the neck having inturned cam shaped flanges, the cap having a centrally raised dome shaped part, the dome shaped part having a central opening, a sheet metal member secured centrally to the cap and having a circular disc shaped central portion, the disc shaped central portion having an opening, the opening having a diameter substantially the same as the major diameter of the said dome shaped portion, the disc shaped portion having flanges, one extending peripherally and the other surrounding the said opening in the disc shaped portion, the disc shaped portion having on opposite sides thereof a pair of radially extending legs substantially U-shaped in cross section and formed integrally with the said central disc shaped portion and protruding from the edge of the said peripheral flange to engage the flanges of the neck whereby the said flanges of the central disc shaped portion operate to prevent egress of the liquid through the opening in the dome shaped portion when shaken.

In witness whereof I have hereunto signed my name to this specification.

GEORGE J. SEISS.
